UNITED STATES PATENT OFFICE.

HARRY M. JACOBS AND AARON J. JACOBS, OF BROOKLYN, NEW YORK, ASSIGNEES TO THE JACOBS BROTHERS CO., INC., OF BROOKLYN, NEW YORK, A CORPORATION OF NEW YORK.

DESIGN FOR A COMBINED SCALE CASING AND PLATFORM.

Application filed October 3, 1927. Serial No. 23,600. Term of patent 14 years.

To all whom it may concern:

Be it known that we, **HARRY M. JACOBS** and **AARON J. JACOBS**, citizens of the United States, residing at Brooklyn, county of Kings, State of New York, have invented a new, original, and ornamental Design for a Combined Scale Casing and Platform, of which the following is a specification, reference being had to the accompanying drawing, forming a part thereof.

The figure is a perspective view of a com-

bined scale casing and platform showing our new design.

We claim:

The ornamental design for a combined scale casing and platform, as shown.

Signed at Brooklyn, in the county of Kings and State of New York, this 28th day of September, 1927.

HARRY M. JACOBS.
AARON J. JACOBS.
